UNITED STATES PATENT OFFICE

2,351,898

AUTOMATIC PRINTER LOCK FOR TYPE-WRITING-ACCOUNTING MACHINES

Robert Anschütz and Fritz Schmidt, Zella-Mehlis,
Thuringia, Germany; vested in the Alien Property
CustodianApplication July 13, 1938, Serial No. 219,076
In Germany July 15, 1937

6 Claims. (Cl. 235—59)

This invention relates to typewriting-accounting machines, sometimes referred to as booking, or bookkeeping machines, and is more especially directed to the means whereby such machines are conditioned to automatically print the calculated totals from the column and from the cross footer totalizers, digit by digit, clearing the totalizers in the process.

Such mechanisms have already become known but have the drawback that it is difficult to equip a machine for cross total taking which is constructed for vertical total taking only.

According to the invention, these drawbacks are eliminated as follows:

A manually operated controlling or total-conditioning member for the cross totalizers, and a manually operated controlling or total-conditioning member for the column totalizers, connect, through a universal member, a driving member which performs the total-taking operation, to a source of power, and locking members holding the controlling members in their active position are arranged to be moved into their active positions with respect to a universal part which is preferably influenced by the movement of the paper carriage, when the controlling members are moved into such active position.

By providing the universal elements aforesaid, disassembling is facilitated.

In the drawings a constructional example of the invention is illustrated.

Fig. 1 is a front elevation of a typewriting-calculating machine equipped with the mechanism according to the invention, the paper carriage being omitted and only its suspension rail, with the column totalizers, being shown.

Fig. 1a is a partial view according to Fig. 1, on an enlarged scale, to give a better representation of the members arranged in this part of the machine.

Fig. 1b is a diagram of the cross totaliser unit illustrated in Fig. 1.

Fig. 2 is a portion of Fig. 1, showing a somewhat modified construction.

Fig. 3 is a plan view of Fig. 1, showing only the front portion of the machine, with the column and cross totalizers omitted.

Fig. 4 is a plan view of Fig. 2, showing the front portion only of the machine, and in which the column and cross totalizers are also omitted.

Fig. 5 is a section through the calculating mechanism on the line a—a in Fig. 4, viewed in the direction of the arrow c, in which the column and cross totalizers are shown but other parts

which are less important for the explanation of the invention, have been omitted.

Fig. 6 is a section through the calculating mechanism on the line b—b in Fig. 4, viewed in the direction of the arrow c, in which the column and cross totalizers are shown, and other parts omitted.

Fig. 7 is a perspective illustration showing the mechanism which controls the automatic total taking from the column and cross totalizers, several parts being shown remote from each other for the sake of clearness.

Fig. 8 is a perspective illustration of the zero arresting mechanisms for the cross totalizers, parts being shown remote from each other.

Fig. 9 is a perspective illustration showing the parts illustrated in Fig. 8, as modified for the machine illustrated in Figs. 2 and 4.

Fig. 10 is a perspective illustration somewhat like Figure 7, but showing the total key mechanism for controlling the total taking from the column and cross totalizers, viewed from the left and the front of the machine.

Fig. 11 is a front elevation of one of the column totalizers.

Fig. 12 is a perspective view supplementing Fig. 10 and showing the controlling member for the column totalizers, and other parts cooperating with the member, also viewed from the left and the front of the machine.

Fig. 13 is another perspective view supplementing Fig. 12, also viewed from the left and the front of the machine, and corresponding to Fig. 8 of Patent 2,347,235 (patent application Serial No. 146,897).

Fig. 14 is a side elevation of the principal parts in Fig. 13.

Fig. 15 is a front elevation of the parts shown in Fig. 13.

Fig. 16 shows diagrammatically a portion of a form filled in with items to be booked by the machine.

Fig. 17 shows a portion of another form to be booked by the modification illustrated in Figs. 2 and 4.

General description of the machine

The principal parts of the machine are the frame 1 (Figs. 1 and 2) which supports the typewriting mechanism, and the paper carriage, not shown. On the suspension rail 8 secured to the paper carriage, the column totalizers 2 to 5 and the dummy totalizers 6 and 7 (Figs. 1, 1a, 2, 5, and 6) are arranged. A wall 9 (Figs. 1 to 6) which supports a calculating mechanism, is ar-

ranged behind the keyboards of the machine. A slotted table 10 is arranged at the right-hand side of the machine below the suspension rail 8, and secured by suitable means to the machine frame. A slide 11 (Figs. 2 and 5) is mounted to reciprocate longitudinally in the slot of the table. On this slide 11, the cross totalisers 12 and 13 are adjustably secured. Pick up bars 14 and 15 connected with the respective cross totalisers 12 and 13 are engageable by that column totaliser 10 which is in active position at the time, to shift the cross totalisers relatively to their respective master wheels 35, 36.

Mounted in the machine frame 1 (Figs. 1 and 3) are the keys 16 of a typewriting keyboard, with carriage shift keys 17, and a carriage return key 18. A sub-frame 19 (Fig. 1) forms a further part of the machine, in which frame are mounted a calculating keyboard 20, a set of decimal tabulator keys 21, a column total taking key 22 (Figs. 1, 3 and 7), a cross total taking key 23 for the cross totalisers (Figs. 1, 3, and 10). A motor 24 secured to the right-hand side of the machine frame operates, through suitable gearing, to drive various elements of the typewriting-calculating machine.

The normal calculating and typewriting operations for the entries required in columns I to IV of the form Fig. 16

For this operation, the column totalisers 2 to 7 are adjusted on the suspension rail 8 in positions corresponding to the columns I to VI of form 25 (Fig. 16). The tabulator carriage stops allotted to the column totalisers but not shown are adjusted on the usual stop bar.

At the same time, the cross totalisers 12 and 13 are adjusted and secured on the slide 11 in the required positions with respect to the column totalisers, or the master wheels. The adjusting and securing operations, however, are performed by the cooperation of a clip 28 (Fig. 5) swingable around a pivot 27 under the influence of a spring 26, with an undercut bar 29 secured to the slide 11. The clip 28 is moved out of clamping position with respect to the undercut bar in the usual manner by its handle 30. After the cross totaliser has been placed in position, it may be held where adjusted by a locking member 31 placed before the handle 30. A nose 32 formed on the handle 30 engages, in the clamping position of the clip 28, a tooth space in a rack 33 secured on the slide 11 (Fig. 5) which is just opposite the nose, and thereby the cross totaliser, or cross totalisers, are held in their positions, as adjusted. For this purpose, the pitch of the rack is, as usually, selected in conformity with the steps of the carriage feed.

The cross totalisers 12 and 13 together form a complementary totaliser or unit K (Fig. 1a), as will be explained more fully below. To this end, the sequence of the numbers on the numeral wheels of the cross totaliser 12 is the reverse of that on the numeral wheels of the cross totaliser 13. The cross totaliser 12 at the left is positive, and the totaliser 13 at the right is negative. In consequence thereof, a total is taken by subtraction in the positive totaliser 12, and a total indicated in positive form may be taken by addition in the negative totaliser 13.

The form 25 is placed around the platen in conformity with the position of the column totalisers 2 to 7, and with its first line in position to be typed. Thereupon, the paper carriage is moved into its final position at the right, for instance, by depressing the carriage return key 18.

In the booking example which will be described, the items of the same kind to be entered in the columns I and III of the form 25 which are indicated and added in the column totalisers 2 and 4, are calculated in positive form in the cross totaliser 12, and the corresponding complementary value appears in the cross totaliser 13. The values to be written down in the columns II and IV of the form are indicated and added in the corresponding column totalisers, and in the cross totaliser 13, but are entered, subtractively, into the cross totaliser 12. Due to the fact that the credit items in columns II and IV are introduced in opposite direction to the debit items in columns I and III, the balance is found which may appear on the debit or credit side, i. e., in the column V or VI of the form 25, in conformity with the ratio of the debit and credit items. That cross totaliser in which the balance then appears, is thereupon placed in cooperative position to the corresponding dummy totaliser 6 or 7, in a manner to be described more fully, by operating that decimal tabulator key 21 which corresponds to the amount of this balance, whereupon the automatic clear writing of the corresponding cross totaliser 12 or 13 forming part of the complementary totaliser unit K can be printed digit by digit in the column V or VI of the form.

In order to effect the bookings in the columns I to IV of the form 25, for example, in its first line, it is necessary to move the paper carriage with the totalisers 2 to 5, or the columns I to IV, respectively, into the operative position required at the time. This is effected by depressing the tabulator key 21 corresponding to the item to be booked. During the consequent movement of the carriage to the left, and therewith of the totalisers 2 to 7, the cross totalisers 12 and 13 forming the complementary totaliser unit K, are automatically coupled to a dog 33a (Fig. 1) of that column totaliser 2 to 7 which moves into active position at the time, by means of the pick up bars 14, 15 (Fig. 3) of the slide 11 (Figs. 1 to 6) which carries the two cross totalisers 12 and 13, so that these partake in the movement to the left. In this operation the denominational wheels of the cross totalisers 12 and 13 are successively moved into driving connection with their respective master wheels 35 and 36 (Figs. 5 and 6) which are mounted to turn on a cross totaliser master wheel shaft 34 (Figs. 1 and 3 to 7) but are held against axial displacement. That column or dummy totaliser which is coincidentally moved into calculating position, comes into driving connection with a master wheel 38 coordinated to all column totalisers (Figs. 3, 4, and 7) and secured on a column totaliser master wheel shaft 37. When the paper carriage, or the totalisers 2 to 7, and the cross totalisers 12 and 13, move into active position, each column totaliser, through controlling cams 39, 40 and 41, secured to the totalisers as required, acts on controlling levers 42 (Fig. 4), 43, (Fig. 9), and 44. Thereby, in a manner to be described more in detail in connection with the total taking operation, the calculating mechanism is unlocked and the species of calculation in the cross totalisers is selected. The controlling lever 44 (Fig. 3) shifts a coupling sleeve 45 mounted to slide axially on the driving shaft 34, to engage the coupling teeth 111 or 112 at opposite ends of the sleeve with coupling teeth 46 or 47 connected to the cross totaliser master wheels 35 and 36, which are also arranged on the shaft 34. A link 102 pivotally connecting the controlling lever 44 to a coupling

arm 103 (Figs. 4 and 9) transmits the movement imparted to the controlling lever 44 from the cams 41 on the column totalisers 2 to 7, to the coupling sleeve 45. In the case of the present booking operation, the teeth 111 and 112 of the coupling sleeve 45 must be engaged with the driving gears 35 and 36 at the same time, and therefore, the link 102 is removed and the controlling lever 44 is rendered inactive. In such instance, the coupling arm 103 which controls the sleeve 45, and is fulcrumed about a screw 108 in the casing of the calculating mechanism, is held in neutral position by a screw M inserted in a hole of its extension 103a and secured in a bracket L (Fig. 7) on the casing of the calculating mechanism.

Before a tabulator key is depressed for releasing the carriage so that it moves to the left, as described, the species of calculation to be performed in the column totalisers 2 to 5 is selected by means of knob 48 (Figs. 1 to 4). Usually, the species is addition, and so the knob 48 is turned so that its index 116 (Fig. 1) is on the mark "A" in the front wall 81 of the calculating mechanism. A tilting member 117 (Fig. 7) is positively connected to the knob 48 and transmits the movement of the knob to a link 120 through a pin 118 engaging in a notch 119 in the link. The link is connected to parts 121 to 127, an arm 122 being equipped with a pin 121 at its upper end, and a slot 293 in the link 120 engaging over the pin. A spring 128 attached to the arm 122 and anchored to a stationary part of the calculating mechanism frame, maintains a connection between the arm 122 and the state control link 120 which is positive in one direction, and yielding in the other.

When the knob 48 is turned as described, an intermediate spur gear 127 is moved into the position illustrated in Fig. 7, as follows: The spur gear 127 is connected to a differential shaft 50 by claws 130 and a clutch disk 131 secured on the shaft, so that the spur gear can be displaced on the shaft but is held against rotation with respect thereto, and, in the position illustrated in Fig. 7, the column totaliser master wheel 38 is rotated through the driving shaft 37 to which rotation is imparted by a train of gears 127, 132, 133, and 134, and this rotation corresponds to addition.

For accounting and writing the items to be booked in columns I to IV, the corresponding calculating keys 20 are depressed, and the values introduced are entered in that column totaliser 2 to 5 which is in calculating position at the time, through the medium of a differentially driven spur gear 49 on the shaft 50 (Figs. 1, 1a, 3, and 4), and the master wheel 38 on the shaft 37, in conformity with the position of the calculating species knob 48. The operative connection of the shafts 50 and 37 is effected by reversing gearing including the gears 127, 132, 133 and 134, as will be described below with reference to total taking.

The mechanism for automatic total taking

The balances calculated from columns I to IV of the form 25 (Fig. 16) in the cross totalisers 12 and 13 which form the complementary unit K (Fig. 1a) may be withdrawn by automatic total taking and typewritten in the columns V and VI of the form 25. Let it be assumed that first the item "125" in the cross totaliser 12 is withdrawn and written in the first line of column V of the form 25. At the same time, the cross totaliser 13 which indicates the complementary value "9999 875," must be automatically returned to

zero. The complementary value must obviously not be written on the form.

In order that the cross totaliser 12 can be cleared, the dummy totaliser 6 must be moved into the corresponding active position, since it controls the cross totaliser 12. This is effected by depressing the "100" tabulator 21. The ensuing movement of the carriage to the left is limited by the tabulator carriage stop (not shown) co-ordinated to the dummy totaliser 6, which stop engages the column selector lever (not shown) co-ordinated to the depressed tabulator key. In this position, the hundreds denominational wheels of the cross totalisers 12 and 13 which have been moved by the dog 33a of the dummy totaliser 6 (Fig. 1) and the pick-up bars 14, 15, are engaged by the cross totaliser master wheels 35 and 36 (Figs. 3 and 7).

The control cam plates 41 (Figs. 5, 6, and 11) of the column totalisers 2 to 7 determine whether the denominational wheels of the cross totalisers shall be rotated additively or subtractively. The cam plate 41 is mounted to slide at the inner side of a front plate 51 (Figs. 5 and 11) of each totaliser 2 to 7 and may occupy three distinct positions. A rib 52 projecting inwardly from the front plate 51 engages in any one of three grooves 53 in the cam plate 41. For the purpose of adjusting the cam plate 41, a clamping screw 54, with a knurled end 55, (Fig. 5) extends through a slot 56 in the front plate 51 (Fig. 11). The position of the control cam plate 41 is indicated by a mark 57 on the cam plate, and marks 59 at both sides of a hole 58 in the front plate 51. The three positions of the cam plate are: Addition, marked "A," release or neutral marked "D," and subtraction, marked "S."

Since in the present example the value indicated in the cross totaliser 12 is additive, it must be withdrawn by subtraction. Therefore, the control cam plate 41 of the dummy totaliser 6 is adjusted for subtraction, "S." When the paper carriage advances, the control cam plate 41 of this dummy totaliser 6 engages the tappet lever 43 (Figs. 3 and 7) which is a bellcrank. The control cam plate 41 turns the bellcrank 43 clockwise about its fulcrum 61 against the action of a spring 60 (Figs. 1 and 7) and a pin 62 at the lower end of the bellcrank engages a reversing lever 63 and a link 64. The link 64 is pivoted to a rocker 65 on a shaft 66, and the bellcrank 43, through the means described, turns the rocker anti-clockwise, and its movement is transmitted to an axially shiftable spur gear 68 by a slide 67, as follows: A pin 69 on the rocker 65 engages in a slot 70 of the slide 67, and a tooth 71 on the slide engages in a groove of the spur gear 68. The spur gear is mounted to slide on the shaft 50 and is held against rotation about the shaft by claws 72 engaging in grooves in the perimeter of a disk 73 keyed on the shaft.

When the spur gear 68 is shifted by the mechanism connected to the rocker 65, which turns anti-clockwise, as described, it moves out of mesh with a pinion 74 on the shaft 34 and into mesh with an idler pinion 75 mounted to rotate in the casing of the calculating mechanism and engaged with a driving spur gear 76 secured on the cross totaliser master wheel shaft 34.

The drive which for addition is from the differential shaft 50 to the cross totaliser master wheel shaft 34 through spur gear 68, and pinion 74, is now reversed for subtraction, since the shaft 50 now drives the shaft 34 through the spur gear 68, the idle pinion 75, and the spur gear 76.

One end of a link 77 is pivoted to the lower end of the bellcrank 43 and slides on a headed screw 80 in the front wall 81 of the machine (Figs. 1 and 2). The link 77 is shifted by the swinging motion of bellcrank 43 in the direction of the arrow C. The lower end 82 of a downwardly extending arm 83 of link 77 is provided with a triangular slot 84 through which extends a headed rivet 87 projecting from an offset lug 85 of the selector lever (see also Fig. 10). The selector lever 86 is mounted to swing laterally and to be shifted upwardly by means of a slot 88 and a headed screw 90 (Fig. 7) extending through the slot. The screw 90 is secured in a bracket 89 and this is attached to a part 92 of the casing for the calculating mechanism by screws 81 (Fig. 1). In its initial position, the selector lever 86 is supported by gravity, the upper end of its slot 88 resting on the headed screw 90. Obviously when the carriage cam 41 (Figs. 5 and 6) wipes over the upper arm of the bell crank 43 (Figs. 7 and 9) to set the cross totaliser reverse gearing 68, 75, 74, 76 to "subtract," such cam and bell crank will shift the link 77 to the left to rock the lower end of the selector lever 86, about the pivot 80.

The resulting clockwise travel of the upper end of the selector lever 86 operates to position a forwardly bent lip 93 formed on a lateral extension 94 of the upper end of the selector lever 86, beneath the right hand one of a pair of adjacently located tails 100 (Fig. 8) projecting from the bell cranks 95 and 96, respectively, to be described below. The selector lever 86 at its lower end has a laterally offset lug 97 provided with an inverted U-shaped slot 98. A headed screw 99 secured in the machine frame (Fig. 1) projects through the slot 98 whereby the selector lever is further guided. As the selector lever 86 is swung clockwise about the bearing screw 90 by the pin-and-slot connection 87, 84, to position its lip 93 beneath the tail 100 (Figs. 1a, 8) of the bellcrank 95, the lug 97 of the selector lever 86 is shifted to position the arm 101 of the inverted U-shaped slot 98 into line with the guiding screw 99.

Since, as described in the paragraph "the normal calculating and typewriting operations . . ." etc., both cross totaliser master wheels 35 and 36 are driven together for the booking operation described, the control cam plate 40 (Figs. 5 and 6) which operates the sleeve 45 (Figs. 4 and 9) is not required in the dummy totaliser 6 and is dispensed with, as well as the lever 44 and the link 102 illustrated in Fig. 9 and omitted in Fig. 7. When the dummy totaliser 6 has moved into calculating position, its control cam 38 acts on the control lever 42 (Figs. 3 and 5) to displace a latch 113 whereby to release a normally effective totaliser locking mechanism 114, 115, for operation.

Preparation of the total taking operation upon depression of the controlling members for the cross totalisers

A bar 135 secured in the sub-frame 19 extends transversely across the machine (Fig. 10) and a controlling member or total key lever 136 for the cross totalisers 12 and 13 is mounted to swing about the bar and held against axial displacement. The cross total taking key 23 for manual operation is secured to the front end of the controlling member 136. A stepped extension 138 projects from the lower side of the controlling member 136 for holding the member

in its initial position and a spring 137 pulls the extension 138 against the rear side of a locking bar 139 which also extends across and is secured in the sub-frame 19.

5 A locking member 140 is fulcrumed on the controlling member 136 at the left about a screw 552 which prevents lateral displacement of the locking member. A spring 141 connecting the members 136 and 140 pulls a tongue 142 of the locking member against the other side of the locking bar 139 and holds the locking member 140 in its initial position.

The rear end of the controlling member or total key lever 136 is laterally offset as at 144 and terminates in a second offset lip 143 which lies beneath the lower end of the selector lever 86 to raise the latter when the controlling member is depressed. Upon depression of the controlling member or total lever 136, the tail 145 of the locking member 140 engages a lug 146 at the upper end of a vertical arm 147 extending from one end of a lever 148. The lever 148 is fulcrumed on a transverse cross brace 150 by a headed screw 149, and its inner end is equipped with a pin 151 engaging in a slot 152 at the inner end of a similar lever 153 fulcrumed on the cross brace 150 at 154. The opposite end 156 of the lever 153 is bent upwardly and equipped with a lug 155 at its upper end for cooperation with parts to be described below. The cross brace 150 has a lug 157 at one end secured to a bracket 160 in the sub-frame 19 by screws 158 (Fig. 1) and its other end is secured to the stationary locking bar 139 by a pair of tongues 161 (Fig. 35) and screws 162.

When the controlling member or total key lever 136 is depressed the tongue 142 of the locking member 140 engages in a groove 163 in the locking bar 139 under the action of the spring 141, holding the locking member 140 and the controlling member 136 in depressed positions. When the controlling member 136 is depressed, a shoulder 164 on the member engages a pin 167 riveted into an ear 165 at the outer end of a lever 166. The lever 166 which is fulcrumed on the inner side of the front transverse bar of the sub-frame 19, at 168 (Figs. 1 and 10), is operatively connected to another lever 171 (Figs. 1, 10, and 12). This lever which is also fulcrumed on the inner side of the front transverse bar of the sub-frame 19 at 172, is bent at its outer end, as at 173 to overlie an offset 174 of a clutch disabling lever 175 journaled on the fulcrum bar 135 alongside a controlling member 176 (Fig. 12) for the total taking from the column totalisers 2 to 5 likewise journaled on the bar 135. By a spring 177 the clutch disabling lever 175 is urged anti-clockwise about the bar 135, and its rear end 175a cooperates with a clutching pawl 178 whereby the eccentric element, here designated 501, 502, is held disengaged from a rotating shaft 504. The total taking controlling member 176 (Fig. 12) for the total taking from the column totalisers 2 to 5 has a lug 179 acting on the offset 174 of the clutch disabling member 175. The tail end of the column totaliser total taking lever 176 can act on a slide 180 which has been shown only partly and on a lever 282, Fig. 12, as will be described.

70 When the total taking key 23 (Fig. 10) for the cross totalisers is depressed, the total taking key lever or 136 is swung about the bar 135 clockwise against the action of its spring 137, and the locking member 140 is moved in the same direction by the spring 141. The tongue 142 of the

locking member 140 slides off the locking bar 139 and then, at the end of the swinging movement, engages in the groove 163 of the locking bar 139 under the pull of spring 141. By these means, the cross totaliser total taking key lever 136 is held depressed.

During the swinging of the members, the rear end 145 of the locking member 140 moves into active position with respect to the lug 146 on the lever 148 by which it is influenced toward the close of the total taking operation, as will be described. The tail 143 of the depressed total taking lever 136 bears against the lower end of the selector lever 86 which, as described, has already been turned clockwise, and raises it. The lip 93 (Figs. 7 and 8) at the upper end of the lever 86 now engages the tail 100 of the bellcrank 95 and the bellcrank together with the mechanism under its control are operated as will be described. If, however, the control cam plate 41 in one of the column totalisers 2 to 5 has been shifted to "E," and this totaliser is in calculating position, the edge 650 (Figs. 1, 2, 7, and 9) of the inverted U-shaped slot 98 in the lug 97 of the lever 86 engages the stem of screw 99 and prevents further depression of the total taking lever 136.

At the same time the shoulder 164 on the depression of the total taking lever 136 engages the pin 167 at the outer end of the toggle lever 166, 171 to press the bent end 173 upon the offset 174 at the front end of the clutch disabling lever 175, to rock the clutch disabling lever clockwise against the tension of spring 177, whereby the rear end 175a of the clutch disabling lever moves clear of the clutching pawl 178. Thereupon a spring 503 engages the clutch pawl with the gear T to couple the eccentric element 501, 502 with the shaft 504 rotated from the motor 24.

The zero stop mechanism for the cross totaliser 12

The bellcrank 95 (Figs. 1a and 8) is fulcrumed on the casing of the calculating mechanism at 181. A link 182 is pivoted to the upper arm of the bellcrank at 183, its other end being connected at 184 to a lever 185. The lever 185 is fulcrumed on the rear wall of the calculating mechanism casing at 186 and its forked upper end 187 engages a pin 188 on a slide 189. The slide is slotted at 190 and a screw 191 in the rear wall engages in the slot for guiding the slide which is supported by a pin 192 in the rear wall. A spring 193 turns the lever 185 about its pivot 186 in anti-clockwise direction and the lever moves the slide 189 to the left. This movement is limited by the end of the slot 190 bearing against the screw 191 and defining the initial position of the corresponding parts.

A flap 195 is mounted to turn about a shaft 194 but held against axial displacement and its tail 196 is engaged with the low inner end 197 of the slide 189 by a spring 198, such engagement serving to press the slide against its supporting pin 192. The shaft 194 is supported by a bracket 197a (Fig. 1a) secured to the front wall 81 of the calculating mechanism by screws 198a. The flap is held against lateral displacement on the shaft 194 between a flange 199 (Fig. 6) of the bracket 197 and an annular check 200 on the shaft 194. A zero stop 203 is secured on an upwardly flanged portion 201 of the flap 195 by screws 202 which zero stop acts on parts of the cross totaliser 12 in a manner to be described below.

A lever 205 (Figs. 6 and 8) is keyed by its hub 75

206 on a release shaft 204 arranged suitably in the calculating mechanism. A push rod 207 is pivotally connected to the upper end of the lever 205 at 208. The free rear end 209 of the push rod is reduced and lies beneath the slide 189. An inclined face 210 is formed on the push rod for cooperation with the slide 189, for a purpose which will be described. The rear end 209 of the push rod is guided in, and supported by, a recess in the rear wall of the calculating mechanism. An inclined face 211 on the slide 189 cooperates with the tail 196 of the flap 195 for a purpose to be described below.

The zero stop mechanism for the totaliser 13

A bellcrank 96 similar to the bellcrank 95, is fulcrumed about the same headed screw 181 (Fig. 8) in the calculating mechanism. To the upwardly projected arm of the bellcrank lever 96 is pivoted a link 213 at 212 and the other end of the rod is pivoted to a lever 215 at 214. The upper forked end of the lever 215 fulcrumed on a headed screw 216 in the rear wall of the calculating mechanism, embraces a pin 218 on a slide 219. The slide 219 is mounted for longitudinal displacement along the rear wall of the calculating mechanism by a slot 220 and a screw 221 secured in the rear wall. It is further guided by a pin 222 secured in the rear wall. A spring 223 engaging the lever 215 swings the lever 215 counterclockwise about its fulcrum screw 216, and the lever pushes the slide 219 to the left. These movements are limited by the end of the slot 220 bearing against the screw 221 in which position the parts mentioned and the members connected to them are in their initial positions. Another flap 224 is mounted to swing about, but held against axial displacement on, the shaft 194 and its tail 225 is in operative connection with a nose 226 of the slide 219. A spring 227 engaging the tail 225 of the flap 224 holds the tail against the nose 226 of the slide 219 and by these means the slide 219 is held against the supporting pin 222. A flange 228 (Fig. 1a) of the bracket 197a and an annular check 229 secured on the shaft 194 hold the flap 224 against lateral displacement on the shaft 194. A zero stop 232 is secured on an upwardly extending front flange of the flap 224 at 231, which stop can act on parts of the mechanism of the cross totaliser 13, as will be described. A lever 233 is secured with its hub 234 on the release shaft 204 which has been described in the paragraph "The zero stop mechanism for the cross totaliser 12." A push rod 236 is pivotally connected to the free end of the lever 233 by a screw 235. The free end 237 of the push rod is reduced and extends beneath the slide 219. An inclined face 238 is formed on the push rod 236 for cooperation with the slide 219, for a purpose which will be described. The push rod 236 is guided in, and supported by, a recess in the rear wall of the calculating mechanism. An inclined face 239 on the slide 219 cooperates with the tail 225 of the flap 224 for a purpose to be described below.

The cross totalizer release shaft 204 on which are mounted the usual unlocking levers 240 (Figs. 5 and 6) for the unlocking of the calculating wheels of the cross totalisers 12 and 13 is operatively connected to the column totaliser release shaft 115 by levers 241 and 243 and a pin-and-slot connection 242. The calculating mechanism unlocking lever 244 for the column totalisers is keyed on the shaft 115.

Operation upon depression of the cross totaliser total taking key 23

When the cross totaliser total taking key 23 (Figs. 3 and 10) is depressed as described, the rear end 145 of the locking member 140 pivoted to the total key lever or controlling member 136, raises the lug 155 at the rear end of the lever 153 through the medium of its own tail 145 and the toggle lever parts 146, 147, 148, 151, and 152, so that the lug bears slightly against a toe 250a (Figs. 10 and 12) at the lower forked end of a depending link 250, suspended from one end of an arm 251 whose other end is fulcrumed about a screw 252 in the rear wall of the calculating mechanism. A pawl 253 is pivoted on the arm 251 about a screw 254. The operation of the pawl will be described below. A spring 255 is connected to the pawl 253 at one end and secured in an eye of the arm 251 at its other end, pulling the pawl against a check B on the arm 251.

As mentioned, the total key lever 136 for cross total taking operates the selector lever 86 which in turn operates the bellcrank 95 (Fig. 8). The bellcrank is pivotally connected to the link 182 and so turns the lever 185 in the same direction and the slide 189 is shifted in the direction of the arrow "n" until the left-hand end of its slot 190 is arrested by the screw 191. During this movement, the inclined face 211 of the slide crowds beneath the tail 196 of the flap 195 and turns the flap clockwise. By these means the zero stop 203 is moved toward the zero setting wheel 125c (Figs. 5 and 6) of the cross totalizer 12 which has previously been moved into writing and calculating position. Each cross totaliser 12, 13 includes a plurality of denominational trains of gears according to the desired capacities of the cross totalisers.

Referring to Fig. 5 it will be noted that each denominational train includes a main gear 261 engageable with and disengageable from the master wheel 35 of the cross totaliser 12. The main gear 261 is connected by an idle or intermediate gear 262 with the corresponding numeral wheel 263, 264 of the denominational train, single numerals on which are visible through a sight aperture in the totaliser casing.

With each such denominational train there is associated as an element thereof, a zero setting wheel 125c (Figs. 5, 6, 8 and 9).

The zero setting wheels are journaled for individual rotation on a rod 125c supported in opposite side walls of the totaliser casing, each zero setting wheel including a toothed pinion 125a and a circular disc 125d, concentric with, but of less diameter than the pinion. Each disc is provided with one or more radial teeth 125e co-extensive with those teeth of the toothed pinions 125a corresponding with the zero positions of the numeral wheels 263, 264.

The zero stop 203 is normally suspended above the path of the zero setting teeth 125e of that disc 125d whose pinion 125a and main gear 261 are in train with the master gear 35, to co-act at the proper time with each denominational gear train brought into operative connection with the master wheel.

The zero stop tooth 203 is so located as to lie only in the path of the teeth 125e of the disc 125d when the zero stop is in effective position.

While these operations are being performed, the shoulder 164 of the cross total taking key lever 136 (Fig. 10) engages the pin 167 of the toggle lever 166, turning the toggle lever clockwise. The toggle lever 166, through the pin-and-slot

connection 169, 170 (Fig. 12), turns the complementary toggle lever 171 in opposite direction to cause its bent end 173 to depress the offset 174 of the clutch disengaging lever 175 and the lever 5 which turns clockwise but does not affect the column total taking controlling member 176. The rear end 175a of the clutch disabling lever now moves away from the clutching pawl 178 of the eccentric unit 501, 502 to enable the arm to turn under the action of its spring 503 (Fig. 12) to engage its tooth 178a between the teeth of the driving gear T. This gear is rigidly connected to the driving shaft 504 while the eccentrics 501 and 502 are rigidly connected to each other but are free to turn on the shaft 504.

The eccentrics now rotate with the driving shaft 504. The eccentric 502 controls an unlocking slide 506 (Figs. 12, 13, 14, and 15) whose lower end supports a roller 507. Springs 508 and 509 (Figs. 12 to 15) hold the roller against the edge of the eccentric 502. As the elevated portion of the eccentric 502 recedes, the unlocking slide 506 descends. An inclined edge 510 on the slide 506 engages a catch 511 of an arm 512 which is free to turn on the unlocking shaft 115, (Figs. 5, 13, and 14), turning the arm clockwise. The arm 512 engages a lug 513 of an arm 514 keyed on the shaft 115 whereby to turn the shaft, unlocking the calculating mechanism. The turning movement of the release shaft 115 is transmitted to the unlocking levers 240 (Figs. 5 and 6) through the parts 243, 242, 241 and the shaft 204. The release lever operates on the locking members 516 individual to the denominational calculating wheels of the cross totalisers 12 and 13.

The cross totaliser release shaft 204 which turns in the direction of the arrow "p" (Figs. 5 and 8) when the cross totalisers are unlocked, shifts the push rod 207 to the rear through its lever 205 (Figs. 6 and 8) to project the inclined face 210 of the push rod into engagement with the slide 189, elevating it. The slide 189, through the tail 196 of flap 195, rocks the zero stop 203 into the path of the zero setting teeth 125e (Fig. 8) of the zero setting wheels 125 of the cross totaliser 12 as the wheels successively arrive in their active positions relatively to the master wheel 35.

When the unlocking shaft 115 is turned as described, a pin 518 (Figs. 13 and 14) on the arm 512 engages the upper edge of a shift lever 519 on a shaft 520 mounted to rotate in the front and rear walls of the calculating mechanism. Levers 521 and 522 are keyed on this shaft. Pins 523 and 524 riveted in the levers engage in the grooved hub of a spur gear 525 mounted to turn freely on shaft 50. Clutching members on the spur gear engage in suitable notches in a flange 526 keyed on the shaft 50.

The shaft 520 is turned clockwise by the pin 518 on the arm 512 against the pull of a spring 527. A depending lever 528 on the rear end of the shift shaft 520 is equipped with a tooth at its free end with which it engages, and is locked by a tooth 529a of a rocker 529 fulcrumed at 530. The turning movement of the shaft 520 is transmitted to the spur gear 525 which is now engaged with the teeth 532 of a zero setting slide 531 mounted to slide vertically in the left hand portion of the calculating mechanism.

Upon the further downward movement of the unlocking slide 506, a dog 533 on the slide engages a pawl 535 pivoted to a catch 534, and turns the pawl. A lug at the end of the pawl 535 engages the catch 534 and turns it clockwise

against a spring 536, withdrawing a tooth at the end of the catch from a rack 537 on the zero setting slide 531, and a rack 538, under the pull of a spring, not shown, now moves the slide downwardly, as indicated by the arrow 543, through pinion 539, shaft 540, pinion 541 and rack 542 on the slide. The rack 538 moves forwardly in the direction of the arrow 544 and, together with a pin 545 on the still descending unlocking slide 506, effect in sequence the typewriting of the value to be withdrawn from the cross totaliser 12.

The total taking operation from the positive cross totaliser 12 in the complementary unit K

Assume that the cross totaliser 12 has been shifted axially to engage the main gear 261 of the hundreds denominational numeral wheel 264 with its cross totaliser master wheel 35 (Figs. 3 and 7), it being recalled that the master wheel shaft 34 on which the master wheel 35 is secured, is connected with the differential shaft 50 by the reversing gear train 76, 75, and 68, which differential shaft is also operable by the zero setting slide 531 (Figs. 13 and 14) through the zero setting gear 525.

When the zero setting slide 531 is released by the unlocking slide 506 for operation, it reversely rotates the driving wheel 261 (Fig. 5) of the hundreds denomination in the cross totaliser 12, and its associated zero setting gear 125a through the mechanism described. The driving wheel 261 is turned in subtractive direction a number of steps equal to the digit registered on the numeral wheel, until the zero setting tooth of the zero setting wheel 125 contacts and is arrested by the zero stop 203 (Fig. 8), at which time the corresponding number wheel 264 (Fig. 5) will have been reversely rotated to display a "0" in the window of the cross totaliser 12 and farther descent of the zero setting slide 531 (Fig. 13) is prevented.

The writing of the number "1" in the first line, column V of form 25 initiated by the zero setting slide 531, is now effected by contact of the pin 545 on the unlocking slide 506 (Fig. 13) with mechanism which has not been shown. The unlocking slide 506 has a constant extent of travel determined by the zero setting eccentric 502, which is not affected by the arrest of the zero setting slide 531 by the zero setting stop 203.

Previously to the printing operation, but after the unlocking slide 506 had completed its descent, a tripping slide 553 at the left of the calculating mechanism (Fig. 13) was shifted in the direction of the arrow 559 through mechanism 554, 555, 556, 557 from the eccentric 501 (Fig. 12) through a stud 558 belonging to the typewriting mechanism by means not illustrated. The operation of the tripping slide trips the rocker 529 whose left arm 560 extends into a slot 561 in the tripping slide 553, to release the locking arm 528. The arms 521 and 522, under the action of the spring 527, shift the spur gear 525 to the left and away from the rack 532 of the zero setting slide 531.

The ascending portion of the eccentric 502 now raises the unlocking slide 506 and the inclined edge 510 of the slide releases the catch 511. The release fingers 240 and 244 (Fig. 5) now return the members 515, 516 into their initial positions, and the hundreds gear train of the cross totaliser 12 is locked again. At the same time, the locking shaft 204 (Fig. 5) is turned in a direction reverse to the arrow p by the parts 243, 242, and 241, and the inclined edge 210 of the push rod 207

(Fig. 8) which is pivoted to the arm 205, is withdrawn from the slide 189. A roller 506a (Figs. 13-15) on the unlocking slide 506 engages a lever 554a fulcrumed in the calculating mechanism, to press the lever 554a upwardly against an eccentric screw 555a in the zero setting slide 531 and returns the zero setting slide 531 into its upper final position, the rack 537 moving idly past the tooth at the upper end of the catch 534.

Obviously during the operation described, the hundreds wheel of the cross totaliser 12 has also been turned for one unit, that is, from "8" to "9," so that now the value "25" is in the totaliser 12, and "9999,975" is in the totaliser 13. The zero setting wheels of the cross totaliser 12 are free to turn as the corresponding zero stop 232 (Fig. 8) was not moved into active position.

When the type bar—not shown—returns, the carriage advances one step to position the tens train of gears of the cross totaliser 12 into operative engagement with the master wheel 35, and the same operations are performed, that is, the "2" is withdrawn from the tens wheels of the cross totaliser 12 while the tens numeral wheel of the cross totaliser 13 moves from "7" to "9," so that now only the value "5" is read on the units numeral wheel of the totaliser 12, and "9999,995" on the numeral wheels of the totaliser 13. The value "2" is written and the totalisers now move to bring the units trains of gears into engagement with their respective master wheels. Here, a similar operation occurs, the value "5" being withdrawn from the totaliser 12. In the totaliser 13, the "5" is added to the "5" there, so that the units wheel registers "0." Upon the transit of the units wheel of cross totaliser 13 from "9" to "0" a tens transfer occurs and all the wheels of higher denominations which register "9" move from "9" to "0." Now, both cross totalisers 12 and 13 are at "0."

When all numeral wheels 264 of the cross totaliser 12 (Fig. 5) are at "0," the half-high-teeth—not shown—of all zero setting wheels 125 by which the clear sign printing device is controlled, are aligned. Under these conditions, a control rail 270 (Fig. 6) extending across the totaliser wheels, can be influenced by the clear sign printing device 273, 272, 271, of known type. When the rail 270 can seat on all the half-high teeth of the zero setting wheels, the clear sign printing can operate.

When the cross totaliser 12 is returned to "0" and the canceled value "125" has been printed in the first line, column V of the form 25, as described, a hook 256 (Figs. 5, 6, and 11) at one end of a plate 550 by which the dummy totaliser 6 is closed at the bottom and which is bent at right angles at its lower end engages the pawl 253 on the arm 251 (Fig. 10) which has been described in the paragraph "Operation upon depression . . .". Since the pawl is in contact with the check B it cannot swing independently but swings the arm 251 anti-clockwise against the action of its spring 551. The depending link 250 (Fig. 10) pivoted to the arm 251 contacts the lug 155 of the tail 153 of the lever 156 and turns the lever anti-clockwise. The movement of the lever 156 is transmitted to the lever 148 through the pin-and-slot connection 151, 152 (Fig. 10) and the lever 148, turning about its pivot 149, causes its lug 146 overlying the tail 145 of the locking member 140 to rock the total key locking member anti-clockwise. The locking member swings about its pivot 552 and is disengaged from the locking bar 139. The cross totaliser

total taking key lever 136 is now free to return into its initial position under the pull of its spring 137, and frees the pin 167 of the lever 168 which is now turned anti-clockwise under the pull of the spring 177 through members 175, 171, 169, and 170. By these means, the tail of the clutch disabling lever 175 returns into the path of the clutching pawl 178 (Figs. 10 and 12) and the eccentric unit 501, 502 is again disengaged from the driving gear T on the driving shaft 504.

Upon its return into initial position, the cross total taking key lever 136 releases the zero stop selector lever 86 which now descends by gravity and its lug 93 releases the lug 100 of the bellcrank 95. Under the action of its spring 193 (Fig. 8) acting on the lever 185, the bellcrank 95 returns into its initial position and moves the slide 189 against the arrow "n" through the link 182. Before this occurs the control cam 39 (Fig. 5) of the dummy totaliser 6 has released the control lever 42 (Fig. 3) which restores to locking engagement with the arm 113 on the unlocking shaft 115 to prevent operation of such shaft, thereby locking the calculating mechanism against operation. The flap 195 (Fig. 8) now returns into its initial position under the pull of spring 198 and shifts the zero stop 203 clear of the zero setting teeth 125e of the wheels 125a in the cross totaliser 12.

At the same time as the control cam 39 releases the lever 42, the control cam 41 of the dummy totaliser releases the state control bellcrank 43 (Fig. 7) to the action of its spring 60, whereupon the state control mechanism is restored to its additive condition, and the cross totaliser selector lever 86 under the control of the link 77 returns into the initial position shown in Fig. 1.

The total taking operation from the negative cross totaliser 13 of the complementary unit K

In the first line of the form 25 (Fig. 16) there was a positive balance "125" in the cross totaliser 12 of the complementary cross totaliser unit K, in the calculation described by way of example. Correspondingly the other cross totaliser 13 of the unit K showed the complement "999,875." This was automatically canceled when totalising from the cross totaliser 12 by the master wheels 35 and 36 which, as described, are connected to each other and at the same time simultaneously engage with wheels of identical denomination of both cross totalisers.

The example illustrated in the second line of the form 25 shows a negative balance "110" in column VI. Assume that this balance has been calculated in the cross totaliser 13 of the unit K, and is to be written in the second line, column VI, it being understood that the complementary amount "999,890" has been incidentally registered on cross totaliser 12.

To this end the control cam 41 of the dummy totaliser 7 is adjusted to "A," as the sequence of the numbers on the number wheels 264 of the cross totaliser 13 is the reverse of the cross totaliser 12.

The "100" decimal tabulator key 21 is now depressed, corresponding to the number "110." The dummy totaliser 7 as it advances in tabulating, picks up and draws with it the cross totalisers 12 and 13 in the same direction by means of the links 14, 15 (Fig. 1a). By these means, the hundreds gear wheels 261 of the respective cross totalisers 12 and 13 are operatively con-

nected to the respective master wheels 35 and 36. At the same time, the control cam 41 of the dummy totaliser 7 moves over the control bellcrank 43 but this is not operated, since the control cam has been moved to "A." The selector lever 86 remains in its initial position, as described in the preceding paragraph, and shown in Fig. 1, and the recess S of its hole 98 is below the stem of the screw 99. As the bellcrank 43 is not operated, an adding operation occurs in the cross totaliser 13. The driving wheels 261 (Fig. 5) of the cross totalisers 12 and 13 are now operatively connected to the shaft 50 through the master wheels 36 (Fig. 7), 35, clutch 45, shaft 34, and reversing gears 74, and 68. Furthermore, the unlocking shaft 115 of the calculating mechanism is unlocked by the cam plate 39 of the dummy totaliser 7 (Fig. 5) acting on the locking lever 42.

When the cross-totalising total key lever 136 is depressed (Fig. 10), the eccentrics 501, 502 (Fig. 12) are reconnected to the driving shaft 504 by the clutching pawl 178 which now engages between the teeth of the driving wheel T on the driving shaft 504. The tail 145 (Fig. 10) of the locking member 140 pivoted on the total key lever 136, engages the lug 146 of the lever 148 and turns the lever anti-clockwise. The movement of the lever 148 is transmitted to the lever 153 by the pin-and-slot connection 151, 152 to press the offset of 185 of lever 153 slightly against the tooth 250a of the depending link 250 suspended from the arm 251, but without raising the link. The tail 143 of the total key lever 136 shifts the selector lever 86 upwardly, so that the lug 93 of the selector lever 86 acts on the lug L (Fig. 8) of the bellcrank 96 and turns the bellcrank clockwise. This movement is transmitted to the swinging lever 215 by link 213 pivoted to it. The swinging lever 215 shifts the slide 219 in the direction of the arrow "n" and the inclined edge 239 of the slide engages below the tail 225 of the flap 224, moving its zero stop 232 close to the zero setting wheel 125 of the hundreds wheel of the cross totaliser 13. When the total key lever 136 has arrived in its lowermost position, it is locked by the tooth 142 of its locking member 140 engaging in the groove 163 of the locking bar 139 where it is held by the spring 141 (Fig. 10).

The eccentric 502 (Fig. 12) now allows the roller 507 (Figs. 13 to 15) at the lower end of the unlocking slide 506 to descend and the slide now operates the catch 511 and, through this, turns the unlocking levers 240 in the direction of the arrow "p" (Fig. 5) to disengage the locking members 516 of the hundreds wheels 261 in the cross totalisers 12 and 13, as described in the paragraph "The total taking operation from the positive cross totaliser 12 in the complementary unit K."

Simultaneously with the unlocking of the cross totaliser wheels, the arm 233 (Fig. 8) keyed on the shaft 204, is turned and the push rod 236 pivoted to the arm, engages below the slide 219 with its incline 238, to elevate the slide and turn the flap 224 farther in clockwise direction whereby to shift the zero stop 232 so that it lies directly in the path of a tooth 125e on the disk 125d of that zero setting wheel 125 in train with the hundreds denominational wheel 261 of the cross totaliser 13.

A lug 533 on the unlocking slide 506 (Fig. 13) unlocks the zero setting slide 531 by acting on a pawl 535. The zero setting slide whose rack

532 has previously been engaged by the pinion 525 under the action of the locking lever 512, now descends eight steps or increments of movement and rotates the shaft 50 which in turn rotates the driving wheels 281 of the hundreds denomination in the cross totalisers 12 and 13 through the train of gears 68 (Fig. 7), 74, 36, and 35. When the zero setting tooth 125e of the zero setting wheel 125x of the hundreds denomination of the cross totaliser 13 engages the zero stop 232 at the completion of the eighth stop, the corresponding number wheel 264 displays "0" in the window of the cross totaliser 13. Also the arrest of the zero setting tooth arrests the descent of the zero setting slide 531 (Fig. 13), at which time the hundreds wheel of cross totaliser 12, which registers the complementary digit "8" of the complementary value 999,890 on the cross totaliser 12, has been advanced by the master wheel 35, in conformity with the value "1" formerly registered on the wheel of hundreds denomination in the cross totaliser 13, so as to register "9" in the cross totaliser 12.

The value "1" is now written in the second line, column VI of the form 25 in the same manner as in the cross totaliser 12 (Fig. 16). The carriage is now letter spaced to position the units wheels 261 of cross totalisers 12 and 13 in engagement with the respective master wheels 35 and 36. Here also, totals are taken in the manner described, and in the cross totaliser 12 a tens transfer occurs from the tens wheel into the hundreds wheel, as a "1" is added to the "9" there registered, so that a tens transfer occurs in each higher place and the corresponding number wheels are brought to "0." When all number wheels 264 of the cross totaliser 13 display "0," all zero setting wheels 125 are aligned with their half-high teeth for clear sign printing whereupon printing is effected as heretofore described.

After the total taking from the cross totaliser 13 has been completed, the eccentric 502 (Fig. 12) returned the unlocking slide 506 into its initial position and the parts controlled by the unlocking slide, for instance, the zero setting slide 531, return into their initial positions. The total key lever 136 is now automatically unlocked in the manner described with respect to the total taking from the cross totaliser 12, and the eccentric unit 501, 502 is uncoupled from the driving shaft 504.

Total taking from the column totalisers 2 to 5

The tail of the column-total taking total key 176 (Figs. 7 and 12) pivoted at 176a is arranged to act on a lug 281 of a lever 282 fulcrumed at 283 on a bracket 282a connected to the lower side of the machine frame. A connecting rod 284 is pivoted to the front arm of the lever 282 at 285. The other end of the connecting rod 284 is pivoted to an ear 286 of a link 287. An open slot 288 at the lower end 289 of the link 287 embraces a pin 291 on the lever 290 of a case shift key 16. There is a slight clearance between the pin and the upper end of the slot, so that the case shift key lever 290 can partake in the depression of the total key lever 176. On the other hand, the total key lever is not influenced by depression of the case shift key 290.

The upper end of the link 287 is pivotally connected to an arm 292 keyed on the reversing gear shaft 125.

When, after the booking of the first three lines of the form 25 (Fig. 16) the column totals of 75

the debit and credit items in columns I to IV are to be written, this is done by writing the values accumulated in the column totalisers 2 to 5. To this end the carriage return key 18 is operated and thereafter the decimal tabulator key 21/"100" is depressed so that the column totaliser master wheel 38 of the calculating mechanism is connected to the driving gear 549 of the hundreds denomination of the column totaliser 2 which corresponds to the value "360," the total in column I. The pick-up dog 33a of the column totaliser 2 draws the cross totalisers 12 and 13 with the column register to engage the hundreds wheels of the cross totalisers with the master wheel 35 and 36, by means of the links 14, 15. The control cam 39 (Fig. 5) of the column totaliser 2 acts on the control lever 42 to release the unlocking shaft 115 of the calculating mechanism.

The vertical column total taking key lever 176 is now depressed (Figs. 7 and 12) and its upper edge 280 acts on a rod 180 which brings the zero stop—not shown—fully into the path of travel of the zero setting teeth on the wheels 570 (Fig. 5), as also described in the said U. S. Patent application, Serial No. 146,897, filed June 7, 1937.

The controlling member 176 also acts on the lever 282 and moves the link 287 in the direction of the arrow "q" in Fig. 7. The upper end of the slot 288 in the link 287 now engages the pin 291 and depresses the lever 290 of the case shift key, to enable a different font of type to print. The link 287 moving in the direction of the arrow q turns the arm 292 anti-clockwise and the arms 123, 122, and 124 partake in this movement. The pin 126 of the arm 124 engages in the groove of the coupling sleeve of the gear wheel 127 and moves the gear wheel 127 into mesh with a gear wheel x keyed on the column totaliser master wheel shaft 37. The pin 121 of the arm 122 slides in the open longitudinal slot 293 of the slide 120 but does not influence the slide.

A locking member 293a is pivoted to the total key lever 176 at 176a. The locking member partakes in the depression of the total key lever and, turning clockwise under the action of a spring 293b, engage in the groove 163 of the locking bar 139 with a tooth 293c (Fig. 10), to retain the total key depressed. The tail 295 of locking member 293a now bears slightly against a second tooth 294 on the lower end of the depending link 250 but does not raise the link.

A shoulder 179 (Fig. 7) at the lower side of the total key lever 176 (Fig. 12) acts on the offset 174 of the clutch disabling lever 175 so that the lever is turned and its tail 175a releases the clutching pawl 178 whereby the eccentric unit 501, 502 which serves for total taking and printing of the totals, is coupled to the driving shaft 504. The unlocking slide 506 (Figs. 13-18) is now released for operation at the start of which it rocks the locking shaft 115 to cause the finger 244 (Fig. 5) to raise the locking member 515 and then free the numeral wheel train of the hundreds denomination in the column totaliser 2 while the known zero stop moves into active position, whereupon the zero setting slide 531 is released and effects subtractive total taking from the hundreds denomination of the column totaliser 2.

The number wheel 546 of the column totaliser 2 (Fig. 5) is driven by the following train of gears: 547, 548, 549, 38 (Fig. 7), 37, x, and

127 from the shaft 50. This shaft also drives the number wheels 264 of the cross totalisers 12 and 13 through the train 68 74, 35, 36, 261, 262, and 263. As the position of the column totalisers 2 to 5 is the same as for the calculations in the first three lines of the form, the value "3" is introduced positively in the hundreds denominational wheel of the cross totaliser 12, as it is cleared from the hundreds wheel of the column totaliser 2.

When the number wheel of the hundreds place in the column totaliser 2 has been returned to "0," the number "3" is printed on the fourth line, column I of form 25 (Fig. 16). The carriage now moves to bring the tens denominational wheels of the column totaliser 2 and of the cross totalisers 12 and 13 into mesh with their register master wheels. After in this manner, progressing from the highest to the lowest denomination, the value "360" has been withdrawn from the column totaliser 2, transferred to the cross totalisers 12 and 13 of the complementary unit K, and printed. As the carriage advances to the letter space, the tooth 256 of the column totaliser 2 (Figs. 5 and 11) strikes the pawl 253 (Fig. 10) and, together with the pawl, turns the arm 251 anti-clockwise so that the depending link 250 descends. Its tooth 294 (Fig. 12) now engages the tail 293g of the locking member 293a and releases the member which now returns into its initial position together with the column total taking key lever 176. The clutch disabling lever 175 is liberated and its spring 177 returns its tail 175a into the orbit of the clutching pawl 178, releasing the eccentric unit 501, 502.

Total taking is now performed in the column totalisers 3 to 5 in a similar manner as described and the corresponding amounts are transmitted to the complementary unit "K" alternately in positive and negative direction, as is known in the art. The totals withdrawn from the column totalisers are printed in italics which is effected by the case shift of the carriage, as described.

The completion of the booking operation

When the added totals of columns I to IV have been written down from the column totalisers 2 to 5, and transferred to the cross totalisers 12 and 13 of the complementary unit K, the balance which has been calculated in the unit in the meantime, is written down in the column V or VI and the booking is then finished. In the present instance, the cross totaliser 12 shows a positive value "5", and the cross totaliser 13 shows the corresponding complementary value 99999,995. The decimal tabulator key 21 for the value "5" is now depressed and the dummy totaliser 6 moves the cross totalisers 12 and 13 with their unit denominational trains into mesh with the driving gear wheels 35 and 36. The case shift key 651 (Fig. 3) is now operated and the key 23 of the cross total taking key lever is depressed whereupon the total registered on the cross totaliser 12 is printed and the wheels returned to zero together with the cross totaliser 13. The value of "5" is written in an italic on the fourth line of the column V.

When total taking has been completed, all parts involved return into their initial positions, as fully described above. The case shift mechanism is returned into initial position by depressing the case shift key 17.

The arrangement for two normal cross totalisers

By way of example, a booking and accounting operation has been described but the machine can also be used for other purposes, such as the calculation of pay, or the like.

As another example a form 600 is illustrated in Fig. 17 in which the freight and passenger trains of two railway lines A and B are booked separately, and added up separately after three days.

The numbers of freight trains in the columns I and III of form 600 are introduced in the column totalisers 2 and 4 and in the positive cross totaliser 12a (Fig. 2), and the numbers of passenger trains in the columns II and IV of the form are introduced in the column totalisers 3 and 5, and in the cross totaliser 13a which is also positive. Finally, each cross totaliser 12a and 13a is cleared independently, and one after the other, the corresponding values are transferred to column totalisers 6a and 7a replacing the dummy totalisers 6 and 7, and written down in the columns V and VI of the form 600.

For this mode of calculation, certain modifications in the machine are necessary, as will now be described with reference to Figs. 2, 4, and 9.

The drive of the cross totalisers 12a and 13a

In order to rotate selectively the gear wheels 35 and 36 which operate the cross totalisers 12a and 13a (Figs. 2, 4, and 9) the screw M which holds the coupling lever 103 in its neutral position, (Figs. 3, 7 and 9) is removed. The link 102 has an extension which is connected to the lever 103 by a screw 106 (Figs. 4 and 9) and its connection to the lever 44 is effected by a screw 105 in a U-shaped arm of the lever 44. A spring 109 is secured to a lug 103b on the coupling lever 103 and its other end is secured to an eye 601 in the rear wall of the calculating mechanism casing (Fig. 4). The spring 109 turns the coupling arm 103 clockwise until its extension 110 bears against the said rear wall. The coupling arm is now in its initial position. By its pin 107 engaging in the groove of the coupling sleeve 45, the coupling arm, when in its initial position, moves the teeth 111 of the sleeve into mesh with the teeth 46 on the hub of the master wheel 35 and this wheel is now in driving position. The control lever 44 is arranged to be turned anti-clockwise by the control cams 48 (Fig. 5) on the column totalisers 3, 5, and 7.

The zero stop mechanism for the cross totalisers 12a and 13a

Since in the example now under discussion either the cross totaliser 13a or the cross totaliser 12a is to be cleared, the zero stop can be controlled in unison for both cross totalisers. This is effected by dispensing with the tail 225 of the flap 224 (Fig. 8), and with the allotted parts 20, 213, 215, 219, 233, and 236, and by combining the zero stops 203 and 232 of the respective flaps 195 and 224 into a single member, as shown in Fig. 9.

As the values to be calculated in the cross totalisers 12a and 13a are introduced additively, the totals calculated in the cross totalisers must be withdrawn subtractively. To this end, the control cams 41 (Fig. 5) on the column totalisers 6a and 7a (Fig. 2) are adjusted to "S" and the control lever 43 is moved clockwise when one of the said column totalisers moves into calculating position. The selector lever 86 is caused

to partake in the movement of the column totalisers, by the rod 11, whereby the slot 101 in the offset lug 97 of the selector lever 86 is positioned below the stem of the screw 99, and the lip 93 positioned below the tail 100 of the bellcrank 95. The bellcrank 95 can now be operated and the zero stop 203, 232 moves toward the paths of the zero setting teeth 125e of the zero setting wheels 125 in the cross totalisers 12a and 13a. In all other positions the selector lever 86—which is operated by the key 23 of the total taking key lever 136—cannot be raised, as in this case its lip 93 strikes against a pin 605 (Figs. 2 and 9) from below. The pin 605 is secured in one arm 606 of an angle member 607 riveted to the inner side of the front wall 81 of the calculating mechanism. Consequently the total taking key 23 can only be operated if the cross totalisers 12a and 13a are cleared by a subtraction operation.

The normal calculating and writing operation under the conditions given by the bookings in the columns I to VI of the form 600, Fig. 17

The column totalisers are adjusted, including their tabulator stops, and the cross totalisers are secured and moved, exactly as described in the paragraphs relating to the form 25 in Fig. 16.

At the beginning of a booking operation in the form 600, the carriage is moved into its final position at the right by depressing the carriage return key 18 (Figs. 1, 3, and 4). Thereupon the tens tabulator key 21 is depressed and the column totaliser 2 (Fig. 2) is moved into calculating position with its tens denominational wheel 549 (Fig. 5) in mesh with the column totaliser master wheel 38 preparatory to the addition of the total "30" on the first line of column I of the form 600 (Fig. 17). The control cam 39 of the column totaliser 2 acts on the bell crank lever 42 to release the latch 113 (Figs. 3 and 5) and free the unlocking shaft 115 for operation, in manner per se known.

Since the column totaliser 2 is without the control cam 40, the lever 44 (Fig. 9) and the coupling sleeve 45 remain in active relation to the cross totaliser master wheel 35. The controlling lever 43 of the state control gear 68, 75, 76, 74, remains in its initial position, since the control cam 41 for the calculating species of the cross totalisers 12a and 13a has been moved to "A" (Fig. 11). The state control gear therefore remains in the addition position determined by the gears 68 and 74. When the value "30" is now calculated in known manner, it is transferred additively into the column totaliser 2 and into the cross totaliser 12a, since the knob 48 (Figs. 1, 3, and 4) has been adjusted to "A."

The column totaliser 3 is now moved into calculating position, in conformity with the value "40," on the first line in column II of form 600, by depressing the corresponding decimal tabulator key 21. In this position, the control cam 40 of the column totaliser 3 acts on the controlling lever 44 (Fig. 9) which is turned clockwise and, through link 102 and coupling arm 103, disengages the teeth 111 of the sleeve 45 from the teeth 46 of the cross totaliser master wheel 35 and engages the teeth 112 of the sleeve with the teeth 47 of the cross totaliser master wheel 36. During the ensuing calculating operation, the value "40" is additively transferred to the column totaliser 3 and to the cross totaliser 13a, the other parts being operated as described with reference to the column totaliser 2. The column to-

talisers 4 and 5 are operated in the same manner as column totalisers 2 and 3.

Total taking from cross totalisers 12a and 13a

When booking has been completed in column IV of the first line in the form 600, the cross totalisers 12a and 13a are cleared successively. The value "55" appears in the window of the cross totaliser 12a and the tabulator key 21 for the tens denomination is operated accordingly. The column totaliser 6a and the cross totaliser 12a are moved into calculating position with their tens denominational wheels engaged with their respective master wheels. The coupling sleeve 45 remains in connection with the master wheel 35 as the column totaliser 6a is without the controlling cam 40, however, the control cam 41 of the column totaliser 6a which has been adjusted to its subtract position, acts on the lever 43 to rock the lever 43 clockwise. The reversing gear which determines the state of the cross totalisers is now set for subtraction through parts 62 (Fig. 7), 63, 64, 65, 69, 70, 67, 71, and the spur 68 is operatively connected to the driving shaft 34 through pinions 75 and 76. The link 77 is moved by the control lever 43 and, in turn, moves the selector lever 86 to position the lug 93 below the tail 100 of the bellcrank 95 and the slot 101 in line with the screw 99.

When the key 23 of the cross totaliser total taking lever 136 is depressed, its tail 143 (Fig. 10) raises the selector lever 86. The lug 93 of the selector lever acts on the bellcrank 95 (Fig. 9) which moves the slide 189 in the direction of the arrow "n" through parts 182, 185, 187, and 188. The incline 211 of the slide now engages below the tail 196 of the flap 195, and the flaps 195 and 224 are now turned clockwise, to advance their zero stops 203, 232 towards the zero setting wheels 125, Fig. 5.

In the meantime, the clutching pawl 178 by which the eccentric unit 501, 502 (Fig. 12) is connected to the driving shaft 504 has been released by members 166, 171, and 175, and the unlocking slide 506 (Fig. 13) is now free to descend. By its incline 510, the slide unlocks the locking levers 515 and 516 (Fig. 5) of the tens denominational trains of the column totalisers 6a, and of the cross totalisers 12a and 13a, and the spur gear 525 (Figs. 13-15) is caused to mesh with the rack 532 of the zero setting slide 531. Simultaneously with the unlocking of the locking levers 515, 516, the slide 207 is moved to the rear by parts 115 (Fig. 5), 243, 241, 204, and 205 (Figs. 6 and 9). The incline 238 of the slide 207 cams the slide 189 upwardly to rock the flap 195, 224 farther in clockwise direction. The zero stops 203 and 232 now come fully into the respective orbits of the zero setting teeth 125e of the zero setting wheels 125 of the cross totalisers 12a and 13a. The zero stop 232 which cooperates with the zero setting wheel of the cross totaliser 13a, is used for a purpose to be described below.

After the zero stops 203 and 232 have been swung, the zero setting slide 531 (Fig. 13) is unlocked by the unlocking slide 506 engaging the pawl 535 and the shaft 50 (Figs. 9 and 13) is rotated. The shaft, through parts 68, 75, 76, and 35, rotates the tens denominational driving wheel 261 in the cross totaliser 12a, the driving wheel being arrested by contact of the zero setting tooth 125e in train therewith, against the zero stop 203 belonging to the cross totaliser 12a, and the return of the number wheel 264 to "0" is now completed. The value "5" which is to be with-

drawn from the tens denominational wheel of the cross totaliser 12a is transferred additively to the corresponding wheel of the column totaliser 6a from shaft 50 through parts 127 (Fig. 7), 132, 133, 134, 37, and 38, and the number "5" is written down in the first line, column V, of the form. The carriage now moves from the tens to the unit place, after the unlocking slide 506 and the zero setting slide 531 (Figs. 13, 14, and 15) have been returned into their initial positions. Otherwise the total taking from the cross totaliser 12a is effected in the same manner as in the first example, and need not be described.

When the cross totaliser 12a has been cleared, the tens key of the tabulator 21 is operated in conformity with the amount "75" present in the cross totaliser 13a. This results in the advancement of the cross totaliser 13a and the column totaliser 7a to bring the tens denominational driving gears into mesh with their respective master wheels. The cross totaliser selecting cam 40 in the column totaliser 7a swings the control lever 44 (Fig. 9) anti-clockwise, so that the link 102 pivoted to the lever 44, and the coupling arm 103 shift the coupling sleeve 45 to mesh its teeth 112 with the teeth 47 of the driving spur gear 38 with its teeth 112. At the same time, the connection between the sleeve 45 and the master wheel 35 is disengaged. The state control cam 41 of the column totaliser 7a which is set to "S" operates the state control lever 43 and, through parts 68, 75, 76 and 36, (Fig. 9) shifts the reversing gear for operating the cross totalisers into its subtraction position. At the same time, the zero stops 203 and 232 are moved into their preliminary positions and the selector lever 88 is swung into its active position. The key 23 of the cross totaliser total taking lever 136 is now depressed, effecting the automatic clearing of the cross totaliser 13a, as described above for the total taking from the cross totalisers 12 and 13. The total taking is completed when the units value "5" has been printed in the first line, column VI of form 600. All parts involved in the total taking operation return into their initial positions, as described.

When the bookings have been performed in the first three lines of the form, and in columns I to VI, the amounts shown in the fourth line of the form 600 which are added in the column totalisers 2 to 5, 6a, and 7a, are written out, as described in the paragraph "Total taking from the column totalisers 2 to 5," and the booking operation on the form 600 (Fig. 7) is now completed. When writing out the amounts from the column totalisers 6a and 7a, the totalisers are placed in their left-hand final position where they are locked by a bolt 700 (Figs. 1 and 1a) so that no values can be registered on the cross totalisers 12a and 13a which have already been set to zero.

Since the basic novel features of the invention are clearly shown and described it will be understood that various omissions, substitutions and changes in the form and details of the devices illustrated and changes in operation may be made by those skilled in the art without departing from the spirit of the invention.

We claim:

1. In a typewriting-accounting machine, the combination with a traveling carriage; a totalizer including a plurality of denominational gear trains; zero stops individual to each gear train; a master wheel with which the denominational gear trains successively engage and disengage; a

normally idle zero arresting device; and a manually settable member; of means to condition the zero arresting device for effective operation, including a rockable and slideable member operable

5 by the manually settable member, for adjustment into and out of effective relation to the conditioning means; and carriage-controlled means to automatically shift the rotatable and slideable member into and out of such effective relation.

10 2. In a typewriting-accounting machine, the combination with a traveling carriage; totalizers, each including a plurality of denominational gear trains; zero stops individual to each gear train; master wheels individual to each totalizer, with

15 which the denominational gear trains of the appropriate totalizers engage and disengage successively; normally idle zero arresting devices spaced relatively to each other and individual to each totalizer; and a manually settable member;

20 of means to condition the respective zero arresting devices for effective operation, including a rockable and slideable selecting member operable by the manually settable member to condition one of the zero arresting devices for effective operation;

25 and carriage-controlled means adjustable to shift the rockable and slideable selecting member differentially to locate said selecting member in position to operate one or another of the zero arresting devices upon depression of the manually settable member.

3. In a typewriting-accounting machine, the combination with a traveling carriage; totalizers, each including a plurality of denominational gear trains; zero stops individual to each gear

35 train; master wheels individual to each totalizer, with which the denominational gear trains of the appropriate totalizers engage and disengage successively; normally idle zero arresting devices spaced relatively to each other and individual to each totalizer; and a manually settable member;

40 of means to condition the zero arresting devices for effective operation, including a rockable and slideable selecting member operable by the manually settable member to condition one of the zero arresting devices for effective operation;

45 carriage-controlled means adjustable to shift said selecting member differentially to locate said member in position to condition one or another of the zero arresting devices for effective operation;

50 upon depression of the manually settable member; and interengaging means on the machine and on the selecting member, respectively, adapted to interlock upon the conditioning of any of the zero arresting devices by the manually settable member, to prevent displacement of the selecting member while the manually settable member remains set.

4. In a typewriting-accounting machine, the combination with a traveling carriage; totalizers, each including denominational gear trains; master wheels individual to the respective totalizers,

60 and with which the denominational gear trains of the appropriate totalizers respectively and successively engage and disengage; reversing gearing for the master wheels; carriage-controlled means adjustable to set the reversing gearing to any of its positions; zero stops individual to each denominational gear train in each totalizer; normally idle zero arresting devices individual to the

65 respective totalizers; and a manually settable member; of means to condition the zero arresting devices for effective operation, including adjustable selective means operable by the manually settable member; and means operable by the carriage-controlled means for the reversing gearing,

to adjust the selective means to position to enable said selective means to condition one or another of the said zero arresting devices upon actuation of the manually settable member, according to the state of the reversing gearing.

5. In a typewriting-accounting machine, the combination with a traveling carriage; totalizers, each including a plurality of denominational gear trains; master wheels individual to the respective totalizers, and with which the denominational gear trains of the appropriate totalizers successively engage and disengage; zero stops individual to the respective gear trains; normally idle zero arresting devices individual to the respective totalizers; and a manually settable member; of means to condition the zero arresting devices for effective operation, including a selecting element adjustable to its effective position relatively to either of the individual zero arresting devices, wherein it is operable by the manually settable member, or to a position out of relation with any of the zero arresting devices; and carriage-controlled means adjustable to differentially actuate the selecting element to shift the latter to any of its adjusted positions.

6. In a typewriting-accounting machine, the

combination with a traveling carriage; totalizers, each including a plurality of denominational gear trains; master wheels individual to the respective totalizers, and with which the denominational gear trains of the appropriate totalizers successively engage and disengage; zero stops individual to the respective gear trains; normally idle zero arresting devices individual to the respective totalizers; and a manually settable member; of means to condition the zero arresting devices for effective operation, including a selecting element adjustable to its effective position relatively to either of the individual zero arresting devices, wherein it is operable by the manually settable member, or to a position out of relation with any of the zero arresting devices; means with which the selecting element co-acts, when in said last-named position for locking the manually settable member against operation; and carriage-controlled means adjustable to differentially actuate the selecting element to shift the latter to any of its adjusted positions.
